UNITED STATES PATENT OFFICE.

JASPER E. MORGAN, OF SPIRO, INDIAN TERRITORY, ASSIGNOR OF ONE-HALF TO JOHN R. HENLEY, OF SAME PLACE.

DESIGN FOR A SHINGLE-GAGE.

SPECIFICATION forming part of Design No. 31,796, dated November 7, 1899.

Application filed September 19, 1899. Serial No. 731,025. Term of patent 14 years.

To all whom it may concern:

Be it known that I, JASPER E. MORGAN, a citizen of the United States, residing at Spiro, Choctaw Nation, and Indian Territory, have invented a certain new and original Design for Shingle-Gages, of which the following is a specification, reference being had therein to the accompanying drawing.

The drawing is a perspective of my new design.

As shown in the drawing, the leading or material feature of my design consists of a pair of wings or flanges 1 1, having a narrow space or groove 2 between them and an integral cross head or bar 3 at right angles with the

wings and a screw-threaded hole 4 extending through one of the wings.

It is obvious that this design is also applicable to gages for other similar purposes.

Having described my invention, what I claim as new, and desire to secure by Letters Patent, is—

The design for a shingle-gage as herein shown and described.

In testimony whereof I affix my signature in presence of two witnesses.

JASPER E. MORGAN.

Witnesses:

C. J. SMITH,
O. L. HENLEY.
